UNITED STATES PATENT OFFICE.

THOMAS LEGGETT STURTEVANT, OF QUINCY, MASSACHUSETTS, ASSIGNOR TO STURTEVANT MILL COMPANY, A CORPORATION OF MAINE.

SCREEN OR SEPARATOR.

1,134,166.

Specification of Letters Patent.

Patented Apr. 6, 1915.

Application filed November 14, 1914. Serial No. 872,138.

To all whom it may concern:

- Be it known that I, THOMAS L. STURTEVANT, a citizen of the United States, residing at Quincy, in the county of Norfolk and State of Massachusetts, have invented or discovered certain new and useful Improvements in Screens or Separators, of which the following is a specification, reference being had therein to the accompanying drawings.
- 10 This invention relates to screens or separators, and more particularly to that class in which the screens are percussively jarred by means of vibrating hammers acting indirectly on the screens.
- 15 The present invention has for its object to provide means whereby the screens will be so mounted or hung that the jarring or vibrating action will be effective, the screens preferably being of such construction that they may be readily dismounted when necessary, and when dismounted may be rolled up so as to be in compact form for convenient transportation.
- 20 In the accompanying drawings Figure 1 is a side view of a separator embodying the present invention. Fig. 2 is a sectional view illustrating a preferred manner of mounting the screens and suitable means for percussively jarring the same. Fig. 3 is a detail sectional view showing a modified construction of sieve mounting and suitable jarring means. Fig. 4 is an enlarged detail view of a portion of the screen mounting construction shown in Fig. 2. Fig. 5 illustrates a modified form of the mounting shown in Fig. 4, and Fig. 6 shows still another form of screen mounting.
- 25 Referring to the drawings, 12 denotes frame parts of the separator supporting an inclined box or casing comprising side walls 13 preferably of sheet steel. To said side walls or casing, within the chamber of the separator, are attached elastic or resilient metallic curtains 14 also preferably of sheet steel, these curtains 14 inclining inward downwardly so that their lower edges are at a considerable distance from the separator side walls 13. The curtains 14 are provided at their lower ends with horizontal flanges 15 to which the screen clothing 16 may be attached either directly, as by rivets, or indirectly. In the construction shown in Fig. 2 the screen clothing is attached to strengthening side bars 17, by rivets or otherwise, the said side bars being provided
- 30 with pins 18 passing through holes in the flanges 15 of the curtains 14, so that the screens may be readily removed or dismounted from the said supporting flanges, and when thus removed or dismounted may be rolled up for convenient transportation. Instead of providing the bars 17 with pins 18 the said pins may be secured to the flanges 15 of the curtains 14, as shown in the detail view Fig. 5, this construction also enabling the screens to be readily dismounted from the said curtains 14 and to be rolled up for convenient transportation.
- 35 In the construction shown in Fig. 3 the curtains 14 are supported by blocks or bars 19 which are preferably removably attached to the sides 13 of the separator frame, and in this construction the screen clothing 16 is riveted or otherwise directly attached to the flanges 15 of the curtains 14.
- 40 In order that the screen clothing 16 may be drawn taut, as is necessary for the best practical use, the curtains 14 are connected with the side walls 13 of the separator frame by means of stretching bolts 20 the heads of which are on the insides of the curtains 13, said bolts being provided on the outsides of the separator walls 13 with adjusting nuts 21 which may be turned for the purpose of stretching the screen clothing taut. The 45 bolts 20 are preferably provided with inside locking nuts 22.
- 45 The screens hung in the chamber of the separator in the manner hereinbefore described may be jarred or vibrated in any suitable manner, as, for example, by jarring mechanism such as that shown and described in the Sturtevant Patents, Nos. 1,035,262 and 1,114,064, this jarring mechanism, as hereinbefore shown, comprising impact bars 24 acted on by vibrating hammers 25 which are lifted by rollers 26 carried by rotating arms 27, the rollers 26 being so arranged as to lift the free ends of the vibrating hammers and then release the same so that they may fall by gravity. Any other suitable mechanism for vibrating or jarring the screens hung in the manner hereinbefore provided for may, however, be employed, as, for example, by providing vibrating hammers 28 acted on by rollers 29 carried by rotating arms 30 and which hammers 28 are arranged to act on the projecting ends of the bolts 20, as shown in Fig. 3. The upper arms of the hammers 28 are suffi-

ciently long and heavy to effect proper action by gravity, or they may be especially weighted, if desired, and said hammers may be prevented from jumping by stops, as 32.

- 5 In the practical use of the invention two or more screens, one above the other (see Fig. 2) will preferably be employed, the upper screen being preferably of coarser mesh than the lower screen, as is usual in separators of the class to which the invention relates. 10 With such an arrangement of screens the impact bars 24 may act directly or indirectly on the upper screen, and the jarring of the impact bars may be imparted to the lower screen through spacing blocks, as 31.

15 From the foregoing it will be understood that the invention, in its preferred form, provides elastic side supports or curtains for the screens, said curtains, the lower edges of which are spaced apart from the side walls of the separator, affording convenient means whereby the screen clothing may be stretched taut; while in the preferred form of the invention the screens are 20 preferably removably mounted on the said elastic curtains so that they may be conveniently placed in position or may be dismounted and when in dismounted condition may be rolled up with said side 25 bars for compactness and convenience in transportation. It will also be understood that the curtains 14 not only serve as convenient means for suspending the screens in such a manner that they are free 30 to be percussively vibrated or jarred, but also serve as shields to prevent the material which is being screened from escaping from the sides of the screens.

While two curtains or shields 14, one at 35 each side of the separator, and both of which are provided with stretching bolts 20 for drawing the screen clothing taut, will preferably be employed, it will be within the present invention to use one yielding 40 curtain or shield and one set of adjustable bolts 20 to enable the screen clothing to be properly stretched, as illustrated in Fig. 6, which shows one side of the screen clothing 45 attached to an angle iron or bracket 33 50 bolted at 34 to a side wall 13 of the separator box or casing.

By the arrangement of the hammers shown in Fig. 3 a crosswise jarring of the screen or screens may be effected, which is 55 very advantageous in sifting some kinds of materials.

The invention is not to be understood as being limited to the details herein shown, as such details may be varied widely within the 60 limits of mechanical skill without departing from the invention. While the suspending curtains or shields will preferably be of sheet steel or other resilient metal, they may, if desired, be of other and somewhat 65 stiff but flexible or elastic material, as thin

sheets of hard wood, which will serve a good purpose under some circumstances.

Having thus described my invention I claim and desire to secure by Letters Patent:

70 1. In a separator, the combination with the side walls thereof, of flexible or elastic shields or curtains suspended from said side walls, wire mesh screen clothing supported by said shields or curtains, and adjustable 75 means, acting through said shields or curtains, for stretching the wire mesh screen clothing.

2. In a separator, the combination with the side walls thereof, of spring-metal 80 shields or curtains suspended from said side walls, a screen comprising wire mesh screen clothing supported by said shields or curtains, adjustable means, acting through said shields or curtains, for stretching the wire 85 mesh screen clothing, and means for percussively jarring the screen.

90 3. In a separator, the combination with the side walls thereof, of spring metal curtains suspended from said side walls, a plurality of superposed screens, comprising wire mesh screen clothing, supported by said curtains, and adjustable means for stretching the said screen clothing.

95 4. In a separator, the combination with the side walls thereof, of inclined spring metal curtains suspended from said side walls, a plurality of superposed screens comprising wire mesh screen clothing supported by said curtains, means for stretching the 100 said screen clothing, and means for percussively jarring said screens.

105 5. In a separator, the combination with the side walls thereof, of spring sheet metal curtains suspended from said side walls and provided at their free lower edges with inwardly extending horizontal flanges, and wire mesh screen clothing supported by said flanges.

110 6. In a separator, the combination with the side walls thereof, of elastic metallic curtains suspended from said side walls and provided at their free lower edges with inwardly extending horizontal flanges, and screens, comprising strengthening side bars 115 and wire mesh screen clothing, supported by said flanges.

115 7. In a separator, the combination with the side walls thereof, of curtains suspended from said side walls and provided at their free lower edges with horizontal flanges, and wire mesh screen clothing removably mounted on said flanges.

120 8. In a separator, the combination with the side walls thereof, of an elastic metallic curtain suspended at its upper edge from one of said side walls, with its free lower edge, which is provided with an inwardly extending flange, separated therefrom, a 125 screen comprising wire mesh screen clothing 130

attached at one side to said flange, means for holding the other side of said clothing, and means, acting through said curtain, for stretching said wire mesh screen clothing.

3 9. In a separator, the combination with the side walls thereof, of an elastic metallic curtain suspended at its upper edge from one of said side walls, with its free lower edge, which is provided with an inwardly 10 exending flange, separated therefrom, a screen, comprising wire mesh screen clothing, attached at one side to said flange, means for holding the other side of said clothing, means, acting through said curtains, for stretching said wire mesh screen clothing, and means for percussively jarring the said screen.

10 10. In a separator, the combination with the side walls thereof, of a metallic curtain suspended from one of said side walls with its free lower edge separated therefrom, a screen, comprising wire mesh screen clothing, connected at one side with said free lower edge of said curtain, means for hold-

ing the other side of said clothing, means, 25 acting through said curtain, for stretching said wire mesh screen clothing, and means, acting crosswise of said screen, for percussively jarring the same.

11. In a separator, the combination with 30 the side walls thereof, of suspended shields or curtains connected at their upper edges with said side walls and having their free lower edges separated from said walls, screens, comprising wire mesh screen clothing, connected with the lower parts of said 35 shields or curtains, means for drawing the lower edges of said shields or curtains apart, so as to stretch said screen clothing, and means, acting crosswise of said screen, for 40 percussively jarring the same.

In testimony whereof I affix my signature, in presence of two witnesses.

THOMAS LEGGETT STURTEVANT.
